UNITED STATES PATENT OFFICE.

ELSIE STEWART, OF GERMANIA, IOWA.

DESIGN FOR A PINCUSHION.

42,340.

Specification for Design. Patented Mar. 19, 1912.

Application filed January 15, 1912. Serial No. 671,363. Term of patent 3½ years.

To all whom it may concern:

Be it known that I, ELSIE STEWART, a citizen of the United States, residing at Germania, in the county of Kossuth and State of Iowa, have invented a new, original, and ornamental Design for a Pincushion, of which the following is a specification, reference being had to the accompanying drawing, forming a part thereof.

The figure is a plan view of a pincushion, showing my new design.

I claim:

The ornamental design for a pincushion, as shown.

ELSIE STEWART.

Witnesses:

E. G. SEYMOUR,

J. M. STEWART.
